UNITED STATES PATENT OFFICE.

GEORGE F. DUNN, OF BROCKTON, MASSACHUSETTS, ASSIGNOR OF ONE-HALF TO
WILLIAM B. ARNOLD, OF NORTH ABINGTON, MASSACHUSETTS.

VAMP THROATING AND MARKING MACHINE.

1,117,955.

Specification of Letters Patent. Patented Nov. 17, 1914.

Application filed October 21, 1909. Serial No. 523,902.

To all whom it may concern:

Be it known that I, GEORGE F. DUNN, a citizen of the United States, and a resident of Brockton, in the county of Plymouth and 5 Commonwealth of Massachusetts, have invented an Improvement in Vamp Throating and Marking Machines, of which the following description, in connection with the accompanying drawings, is a specification, like letters on the drawings representing like parts.

This invention relates to dieing and marking machines and more particularly to machines for throating and marking the vamps 15 of boots and shoes, and among other objects provides means for accurately positioning vamps beneath a throating die, and adjustable means for marking the vamps.

The character of the invention may be 20 best understood by reference to the following description of an illustrative embodiment thereof shown in the accompanying drawings wherein:

Figure 1 is an end elevation of a vamp 25 throating and marking machine embodying my invention; Fig. 2 is a side elevation of Fig. 1; Fig. 3 is a vertical section, taken on line 3—3 of Fig. 1; Fig. 4 is a plan of Fig. 1 with the cutter die and its support 30 removed; Fig. 5 is a horizontal section, taken on line 5—5 of Fig. 1; Fig. 6 is a horizontal section taken on line 6—6 of Fig. 2; and Fig. 7 is a section taken on line 7—7 of Fig. 5.

The illustrative vamp throating and marking machine shown herein as embodying my invention comprises (Fig. 1) a die block 7, supported on the usual table 9, rotatable about the central post 10 (Fig. 4) projecting upwardly from the machine base 11. The upper periphery of said table 9 is provided with a rack 12 adapted to coöperate with the usual devices, (not shown) for intermittently turning the table to distribute 40 the wear on the surface of said block.

To cut the work on the die block a U-shaped throating cutter die 13 (Figs. 2, 3, 5 and 6) is provided of flexible ribbon metal sharpened on its lower edge and is carried by a frame 15, secured to a vertical post 16, which may be vertically reciprocated 50 in any suitable manner to cause the cutter

to descend at the proper times toward the die block to cut the work thereon. To adjust the die to cut throats of various sizes 55 the legs of the die may be mounted in carriers 17 and 18 (Figs. 3 and 6), having respectively upwardly projecting studs 19 and 20, extending through diverging elongated slots 21 (Fig. 5) in a horizontal plate 22 60 secured to and depending from the frame 15. These studs also extend through elongated slots 23 in a sliding plate 24, superposed on the plate 22, the latter slots being substantially perpendicular to the median line 65 of the cutter die, and cross the diverging slots 21 referred to. It will be apparent that by sliding the plate 24 on the plate 22 the studs 19 and 20 and the cutter leg carriers 17 and 18 will be caused to approach 70 or recede from each other according to the direction in which the sliding plate 24 is moved. The curved end or bend 13^a of the U-shaped cutter may be positively adjusted to conform to the adjustment of the 75 supports for the legs of the cutter by a narrow, sliding end carrier 25 (Figs. 3 and 6), guided between triangular shaped guides 25^a (Fig. 6) secured to the under face of said plate 22, the diverging edges 25^b of said 80 guides also constituting guides for the in-curved ends of the cutter leg carriers 17 and 18. The carrier 25 has a depending projection 25^c curved to conform to the curvature of the cutter, said cutter being 85 received between said projection and the curved, depending end of a strip 26 screwed or otherwise secured to said sliding carrier 25. To move this carrier with the plate 24 referred to, a stud 27 is secured to said 90 carrier and projects up through an elongated slot 28 (Fig. 3) in the plate 22 and is secured at its upper end to said plate 24. The plate 24 may be slid on the plate 22 by means of a screw 36, having an end threaded 95 into a lug 37 extending upwardly from the plate 24. The opposite end of said screw is journaled in a bearing in an upturned end 38 of the plate 22 (Fig. 2), and is provided with a suitable handwheel 39. The screw 100 36 is capable of rotation in its bearing but is prevented from longitudinal movement therein by suitable collars. As a result, when the handwheel 39 is rotated the lug

37, with its plate 24, will be slid causing the cutter to expand or contract as desired. It will be apparent that as the leg supports approach, the curved portion of the cutter 5 will be shorter and the straight portion or legs of the cutter will be proportionately longer.

To permit said legs to slide in their supports to conform to the narrowing or widening 10 of the curve or bend of the cutter they are not fixed to said supports but are adjustably supported in their carriers by pins 29 (Figs. 3 and 6) projecting through the legs of said cutter and received by elongated 15 slots 29^a in said carriers 17 and 18.

To prevent the vamps or the throat blanks cut from said vamps from being pulled up from the die block with the cutter after the cut is made, a stripper may be provided for 20 said cutter. Herein a stripper plate 30 (Figs. 3 and 6) smaller than but of a shape similar to said cutter is supported within the latter by guiding studs 31 received by hollow posts 32 depending from the plate 22. The stripper plate 30 is supported by a central plunger 33 entered into a hole 33^a in the plate 22, said hole being counterbored to receive a head 34 on said plunger. This head is normally seated at the base of said 25 counterbore by a spring 35 encircling said plunger and compressed between the under face of the plate 22 and the stripper plate. When the cutter descends to cut the throats in the vamps the stripper shares in this de- 30 scent until it comes in contact with the top vamp when its movement is arrested by its engagement therewith. As the cutter continues downwardly to cut through the vamps the base of the counterbore withdraws from 35 under the stud head 34 and the spring 35 is compressed. When the cutter ascends the stripper will press the vamps down until after the cutter is above said vamps. The continued upward movement of the cutter 40 will cause the plunger head 34 again to be seated on the base of said counterbore and the stripper will be drawn up from engagement with the vamps.

The downward movement of the frame 15 50 is utilized not only to cut the throats in the vamps but also to mark the latter for any desired purpose, as to indicate the position of the shoe tip on the vamp. To this end vertical marking pins 40 are provided 55 (Figs. 1, 2, 3 and 5) and may receive adjustment corresponding or conforming to the adjustment of the cutter die, by passing said pins through diverging elongated slots 41 (Figs. 5 and 6) in the plate 22 referred 60 to and upwardly through guide wings 42, each provided with elongated slots 43 extending substantially perpendicular to the cutter die median line, and crossing the diverging slots 41. These pins may occupy 65 stripper sleeves 45 the upper ends of which

are provided with collars 47 adapted to rest on the upper surface of the wings 42 and prevent said sleeves from dropping through the slots. To support the marking pins 40 the latter are provided with heads 51 which may be yieldingly supported by helical springs 53, encircling said pins and compressed between the collars 47 and said heads 51. To permit the pins to be adjusted and slid in said cross slots as described 70 these heads 51 are yieldingly pressed by said springs into sliding engagement with horizontal bridge bars 55 (Figs. 1, 2 and 5), which diverge similarly to the slots 41 and are supported at their ends above the plate 22 by spacing sleeves 57, secured to said plate by suitable bolts 59. When the cutter die descends to cut the vamps the stripper sleeves 45 share this movement until they come into contact with the top vamps, when they are arrested by their engagement therewith, the continued downward movement of the cutter die causing the marking pins 40 to descend against the resistance of the springs 53 and project through the stripper sleeves and penetrate or mark the vamps. When the cutter die is moved upwardly away from the vamps the stripper sleeves 45 will remain in contact with the surface of the top vamp and cause the vamps to be stripped from the marking pins 40. By the time the marking pins have passed above the lower ends of the stripper sleeves the stripper sleeve collars 47 will be engaged by the wings 42 and will continue upwardly with 90 the die.

The marking pins 40 hitherto have been adjusted simultaneously and in conformity with the cutter die adjustment as by connecting the marker guides directly to a nut on the screw 36 thereby causing the markers to share directly the adjustment of the die. By my invention the marker guides may not only be adjusted in conformity with the cutter die to correspond to the size of vamp throat cut, but a gage is provided for said markers whereby they may be given a preliminary adjustment relatively to said die, so that, among other things, when marking the positions of shoe tips the distance from the vamp throat or die to the inner edge of the tip may be varied as desired. This gage comprises the marker guide wings 42 referred to which are secured to or form parts of vertical guide plates 61 (Figs. 1 and 5), said plates being provided with dovetailed projections 63, which are received by similarly shaped horizontal grooves, in a nut 65, threaded on the cutter die adjusting screw 36 at a point between the lug 31 and the bearing end 38. These opposed guide plates are connected by a bridge plate 67, the latter having a threaded opening receiving an adjusting screw 69 provided with a handwheel 70, said screw being journaled 110

in an open bearing 71 in a lug 73 projecting upwardly from the nut 65. The screw is capable of rotation in said bearing but not of longitudinal movement relative thereto.

5 When the die adjusting handwheel 39 is rotated to vary the adjustment of the cutter die the nut 65 will travel on the screw 36 causing the marker guide wings 42 to share in this movement and be adjusted in conformity with the adjustment of the throating die for the size desired. By turning the handwheel 70 of the preliminary adjustment screw 69, the marking pin adjusting wings 42 may be slid relatively to and independently of the nut 65 to vary the distance of the marking pins from the curved end of the cutter die, furnishing several adjustments for each adjustment of said die. This is found to be a very advantageous construction, since the length of the vamp between the throat and shoe tip may be varied irrespective of the throat cutter adjustment. The independent marker adjustment is equally advantageous in marking points for 25 bluchers and other purposes as desired.

To accurately set the marking pins in predetermined preliminary positions of adjustment the gage referred to (Fig. 5) includes indicating means comprising a graduated scale 77^a on a plate 77 which is mounted in a groove in the top of one of the marker guide plates 61, said scale being adapted to be read against an index pointer 78 (Fig. 5) secured to one side of the adjusting screw lug 73. Said scale is herein divided into three divisions, indicating marker adjustments for shoe widths 1 to 6, each line indicating two widths.

To accurately and simultaneously set the cutter die and markers into predetermined positions of adjustment, indicating means are provided including a graduated scale 79^a on a plate 79 (Figs. 1 and 5) mounted in a groove in the top of the plate 22, said scale plate being herein divided transversely into widths from 1 to 6, and longitudinally into sizes numbering from 5 to 11, inclusive, for each of said widths. Said scale may be read against an index edge 81 of one of the marking pin adjusting wings 42 which slides over said plate 79. In using the indicating means shown herein the marker pins may be given a preliminary adjustment relatively to the throating die by turning the small hand-screw 70. As illustrated herein the scale line 5—6 is set in line with the index pointer 78. After this preliminary adjustment is made the large handwheel 39 is turned to cause the cutter legs to approach or recede to give the desired cutter adjustment and to give the final adjustment of the markers, bringing the wing reading index 81 in line with any of the sizes in either of the rows of size figures indicated by widths 5 and 6 on the

margin of said scale plate 79. As illustrated herein the edge 81 is set in line with size 8 of width 5. If the preliminary adjustment is on line 3—4, the final adjustment may be on any of the sizes in either of the rows of size figures indicated by widths 3 and 4 on the margin of said scale plate 79. And if the preliminary adjustment is on line 1—2, the final adjustment may be on any of the sizes in either of the rows of size figures indicated by widths 1 and 2 on the margin of the scale plate 79. As a result the markers may be adjusted independently of said die. As shown herein the distance between the die and the markers increases as the widths are changed from 5—6 to 1—2.

The styles of shoe caps or tips change from time to time and to provide indicating means of sufficient range to indicate any length of cap or any extent of vamp between the curved end of the vamp throat and the edge of the shoe cap the capacity of the scale 77^a on the plate 77 may be increased by sliding said scale plate in its groove. To accurately indicate the adjusted positions of the plate 77 the latter is provided with what may be termed a style scale 77^b which may be read against an index line 77^c on an edge portion of the top of one of the guides 61. Herein this scale is divided into divisions numbered from 1 to 4, but any number may be used as desired. The plate may be secured in its adjusted positions by a set screw 77^d entered through a slot 77^e.

In a similar manner the range of the scale 79^a may be increased by sliding the scale plate 79 in its groove and its positions of adjustment may be indicated by a style scale 79^b (Fig. 5) divided into divisions, herein also numbered from 1 to 4, said divisions being adapted to be read against an index line 79^c on said plate 79. This plate may be secured in its adjusted positions by a set screw 79^d entered through a slot 79^e in said plate.

It will be apparent that when said plates 77 and 79 are in the positions shown in Fig. 5 a number of indicated adjustments may be effected as previously described, but by sliding said plates and with reference to the style scales 77^b and 79^b a new set of adjustments may be had by the scales 77^a and 79^a with each of the divisions of the style scales 77^b and 79^b as a nucleus.

In using the machine a great many vamps may be cut of one size, and the machine may not need to be adjusted with much frequency, but when it is desired to cut vamps of different sizes and with different markings, the adjustments may be very easily and quickly made, by simply turning the handwheels with reference to the indicating means, as described.

An important feature of my invention consists in providing means whereby vamps may be accurately positioned on the die block beneath the cutter. To this end the 5 supporting area of the block is supplemented by a horizontal plate 83 (Figs. 1, 2, 3 and 4) detachably connected to the base 11 by vertical studs 85 projecting downwardly from the plate 83 and having reduced ends 10 87 adapted to be received by hollow posts 89 projecting upwardly from the base 11. The inner portion of this plate adjoins the die block 7 on a level therewith, and is shaped to conform to the peripheral contour 15 thereof. The side edges of the plate 83 are provided with guides 91 (Figs. 4 and 7) which extend beyond the plate 83 and overlie the die block 7 for a substantial distance. Mounted to slide on said block is a vamp 20 supporting tray 93, (Figs. 1, 4 and 7) of sheet material and having side strips 94 secured thereon and adapted to slide in said guides 91. The tray has a U-shaped cut away portion 95 sufficiently large to permit 25 the throating die to pass through said tray for any adjustment of said die. The inner end of this tray is provided with a transverse cleat or stop 97 (Figs. 3 and 4) herein of angle iron secured thereto. One or 30 more vamps may be accurately positioned on said tray 93 by long, curved guide fingers 99, 101, resting on the tray 93 and adapted to slide toward and from each other to center and accurately position 35 the vamps on the tray with their ends abutting against the stop 97. The guide fingers 99 and 101 may be adjusted toward and from each other by an oppositely threaded screw 103, rotative in, 40 but incapable of longitudinal movement in a bearing box 105, secured to the side of an upwardly extended end 107 secured to said tray. To contribute to the guidance of the fingers 99, 101, their screw receiving ends 45 109 are enlarged and squared, to slide against the face of said end 107 and the adjacent surface of the tray 93. The screw 103 may be turned to move said fingers toward or from each other by a suitable hand- 50 wheel 111. Since the opposite outer edges of a vamp are not symmetrical, the guide finger 99 is provided with a curvature somewhat greater than that of the finger 101. Vamps for right and left shoes may be cut 55 in a single operation by superposing some of the vamps with their smooth sides up and others with their rough sides up. To permit the marking pins to pass through the tray in any of their positions of adjustment, said tray is provided with oblique, 60 elongated slots 113.

To accurately position the vamp-receiving tray beneath the cutter die and into positions corresponding to the cutter die and 65 marker adjustments, a stop 115 (Figs. 1,

2, 3 and 5) is mounted on the sliding, adjusting plate 24 for the cutter. Herein this stop is in the form of a narrow strip secured onto said plate adjacent the screw lug 37. This strip extends horizontally from 70 said plate over and beyond the plate 22 and thence is bent vertically downwardly to bring an edge 117 of its depending end adjacent one of the tray guides 91 as well shown in Figs. 2 and 5. Coöoperating with 75 this stop is a tray positioning gage (Figs. 1, 2, 4, 5 and 7) secured to one of said side strips 94 (Fig. 7). This gage comprises a block 121 hollowed out horizontally to receive a longitudinally sliding 80 sleeve 123 which may be interiorly threaded to receive an adjusting screw 125. The shank of this screw is rotative in a bracket 127 (Fig. 2) secured to an end of said block and is prevented from longitudinal movement therein by collars 129. The gage is provided with indicating means comprising a scale 131, herein on the top of the block 121 (Figs. 4 and 5). Said scale may be divided into divisions numbered to indicate adjustments for vamp sizes from 5 to 11. To indicate the positions of adjustment of said sleeve the block 121 is slotted to receive a T-shaped index 133 secured to said sleeve and movable therewith. The 95 scale may be read against the edge 135 of said index.

In use, the tray is slid from beneath the cutter die out onto the supporting plate 83. One or more vamps 136 (Fig. 3) are then 100 placed on the tray with their ends abutting against the stop 97. The handwheel 111 is then turned to cause the fingers 99 and 101 to approach and accurately center and maintain the vamps in their superposed positions. The cutter die and markers having been adjusted as described to cut, for example, the proper throat in a vamp, size 8 width 5 (as shown) the tray gage screw is turned to bring the index edge 135 in 105 alignment with the line indicating size 8 on the scale 131. The tray is then slid in under the cutter die 13 until the outer end of the index sleeve 123 abuts against the edge 117 of the depending stop 115 whereupon 115 the vamps are accurately positioned to receive the proper length of throat to conform to the size of the cutter adjustment. After the die has descended and cut the throats of the vamps the tray 93 may be 120 slid out from beneath the die until the curved portion of its U-shaped opening 95 projects beyond the outer edge of the tray support 83. A slight downward pressure on the throat blanks, remaining in the throat 125 after the cutter is withdrawn, will cause the ends of said blanks to project down through the opening 95, permitting them to be readily pulled therethrough.

It will be understood that my invention 130

is not limited to the particular embodiment shown herein, but that various modifications may be made without departing from the spirit and scope of my invention.

5 Claims:

1. A machine of the class described comprising, in combination, a vamp throating die, means to adjust the same for throats of different sizes, and vamp receiving means for positioning vamps beneath said die in positions conforming to the adjustment of said die.

15 2. A machine of the class described comprising, in combination, a vamp throating die, means to adjust the same to produce throats of different sizes, and vamp receiving means for positioning vamps beneath said die in positions determined by the size adjustment of said die.

20 3. A machine of the class described comprising, in combination, a die block, vamp receiving means adapted to slide thereon and guide means on said receiving means for positioning vamps thereon independently of 25 the position of said vamp receiving means on said block.

30 4. A machine of the class described comprising, in combination, an adjustable vamp throating die and means to position vamps beneath the same including a gage coöperating with said die.

35 5. A machine of the class described comprising, in combination, an adjustable vamp throating die, a die block, a vamp supporting tray adapted to slide on the latter and gage means coöperating with said die for positioning said tray beneath said die.

40 6. A machine of the class described comprising, in combination, an adjustable vamp throating die, a die block, a vamp supporting tray adapted to slide on the latter, and gage means for centering said tray beneath said die to positions determined by the adjustments of said die.

45 7. A machine of the class described comprising, in combination, an adjustable throating die, a die block, and vamp supporting means for centering vamps beneath said die including gage means coöperating with said die and having means for indicating the adjustments of said vamp supporting means.

50 8. A machine of the class described comprising, in combination, a die, adjusting means therefor and means coöperating with the latter to position articles beneath said die.

55 9. A machine of the class described comprising, in combination, a vamp throating die, adjusting means therefor, means adjustable to the latter for determining position of vamps beneath said die and means for indicating the adjustments of said die and positioning means.

60 10. A machine of the class described com-

prising, in combination, a die, adjusting means therefor, a stop connected with the latter and means coöperating with said stop to position articles beneath said die.

65 11. A machine of the class described comprising, in combination, a vamp throating die and markers, adjusting means therefor and means coöperating with the latter for positioning vamps beneath said die and markers.

70 12. A machine of the class described comprising, in combination, a vamp throating die, adjusting means therefor, a stop connected with the latter, means for positioning vamps beneath said die and gage means on the latter means coöperating with said stop.

75 13. A machine of the class described comprising, in combination, a vamp throating die, adjusting means therefor, a stop movable with the latter, a vamp positioning tray for said die and a gage on said tray coöperating with said stop.

80 14. A machine of the class described comprising, in combination, a vamp throating die, an adjusting plate therefor, a stop depending from said plate, a vamp positioning tray adapted to be slid beneath said die and a gage on said tray coöperating with said stop.

85 15. A machine of the class described comprising, in combination, a vamp throating die, adjusting means therefor, vamp positioning means and a gage thereon comprising a scale and index means coöperating with said adjusting means.

90 16. A machine of the class described comprising, in combination, a vamp throating die, adjusting means therefor, a stop movable with the latter, vamp positioning means and a gage thereon coöperating with said stop comprising a block, a scale thereon and sliding means within said block having an index adapted to be read in connection with said scale.

95 17. A machine of the class described comprising, in combination, a vamp throating die, adjusting means therefor, a stop movable with the latter, a vamp positioning tray, a gage block thereon, a scale on said block, a sleeve adapted to slide in the latter and having an index thereon and an adjusting screw for said sleeve.

100 18. A machine of the class described comprising, in combination, a substantially U-shaped, flexible cutter, independent means for carrying the legs and bend of the cutter and unitary means for adjusting said carrying means.

105 19. A machine of the class described comprising, in combination, a substantially U-shaped, flexible cutter, carriers for the legs and bend of the same and a sliding plate for simultaneously adjusting said legs and bend.

110 20. A machine of the class described com-

prising, in combination, a substantially U-shaped, flexible cutter, carriers for the legs and bend of the same and relatively movable plates having cross slots for adjusting said legs toward or from each other and means secured to one of said plates for adjusting said bend carrier.

21. A machine of the class described comprising, in combination, a substantially U-shaped, flexible cutter, carriers for the legs and bend of the same, studs projecting upwardly from said carriers, and superposed sliding plates having cross slots for receiving said leg carrier studs, said bend carrier stud being entered through a slot in one of said plates and secured to the other.

22. A machine of the class described comprising, in combination, an adjustable vamp throating die, a die block, a vamp positioning tray adapted to slide thereon and having an aperture therein through which the throat material cut out by said die may be ejected.

23. A machine of the class described comprising, in combination, a support having guide means thereon, a vamp-receiving tray having provision permitting its manual ad-

justment along said guide means to and from a position beneath a die, opposed fingers curved to conform to the contour of the side edges of the vamp, and means connecting said fingers to said tray having provision permitting the adjustment thereof to accommodate vamps of different sizes.

24. A machine of the class described comprising, in combination, a support having guide means thereon, a vamp-receiving tray having provision permitting its manual adjustment along said guide means to and from a position beneath a die, a stop on said tray, opposed fingers on said tray curved to conform to the contour of the side edges of the vamp, and means connecting said fingers to said tray, having provision permitting the adjustment thereof to accommodate vamps of different sizes.

In testimony whereof, I have signed my name to this specification, in the presence of two subscribing witnesses.
